ARROW RELEASING DEVICE

Harry J. Rose, West Allis, Wis., assignor to Make-
All Tool & Die Co., West Allis, Wis., a corpora-
tion of Wisconsin

Application August 3, 1950, Serial No. 177,520

3 Claims. (Cl. 124—35)

1

This invention relates to improvements in arrow releasing devices.

In archery, the arrow nock is engaged with the string of the bow and, under conventional practices, it is so held by the fingers of the archer while the string is pulled, the arrow nock and string being ultimately manually released, causing the shooting of the arrow in the desired direction. The above conventional practice in respect to shooting an arrow from a bow makes the accuracy of the shot dependent upon the operation of the archer's fingers in releasing the arrow nock from the taut string of the bow. Even with an expert archer there is lack of uniformity in respect to repeated manual releases of arrows. The conventional practice furthermore is hard on the fingers, hand and arm of the archer and some archers find it necessary to wear finger gloves and arm guards.

With the above in mind it is, therefore, a primary object of the present invention to provide an arrow releasing device which, through operative mechanical means, engages the arrow nock with the taut retracted string of a bow and permits the uniform and smooth release of the arrow nock from the taut bow string without being dependent upon the direct grip and release by the fingers of the archer.

A further object of the invention is to provide an arrow releasing device in the nature of a trigger operated pistol grip which, when set, mechanically secures the arrow nock to the bow string and which is operative to mechanically release the arrow from the taut string for shooting purposes, insuring a uniform and smooth release of arrows from the bow upon each shot.

A further object of the invention is to provide a mechanical trigger operated arrow releasing device which secures an arrow to a bow string in a manner so that the frictional restraint on the engaged arrow is always uniform.

A further object of the invention is to provide an arrow releasing device in the nature of a trigger operated pistol grip which, for shooting purposes, is easy to operate and eliminates the need for the wearing of gloves or arm guards by the archer.

A further object of the invention is to provide a mechanical arrow releasing device which will accommodate arrow nocks within the conventional size deviations and in which a friction spring bearing on the engaged arrow nock is adjustable to adapt it to arrow nocks of varying diameters.

A further object of the invention is to provide

2

an arrow releasing device which is of very simple construction, is simple and accurate in its operation, which may be used with all standard archery bows and arrows, and which is well adapted for the purposes described.

With the above and other objects in view, the invention consists of the improved arrow releasing device and its parts and combinations as set forth in the claims, and all equivalents thereof.

10 In the accompanying drawing in which the same reference characters indicate the same parts in all of the views:

Fig. 1 is a fragmentary side view of a bow having the string thereof taut or retracted and releasably engaging the nock of an arrow by means of the improved arrow releasing device;

15 Fig. 2 is an enlarged fragmentary view of one side of the arrow releasing device with a plate removed to show the internal mechanism, the plate retaining screws being in section;

20 Fig. 3 is an enlarged front view of the portion of the arrow releasing device shown in Fig. 2, releasably engaging an arrow nock and bow string, the arrow nock being shown in section;

25 Fig. 4 is an enlarged fragmentary view of the arrow releasing device showing the side portion thereof opposite that shown in Fig. 2; and

30 Fig. 5 is a fragmentary detail sectional view taken on line 5—5 of Fig. 3.

35 A conventional archery bow is indicated by the numeral 8 and it includes a string 9 secured at its ends to the ends of the bow (not shown) and adapted to be drawn rearwardly to a taut position for arrow shooting purposes. A conventional arrow for use with the bow is indicated by the numeral 10. The rear end portion of the arrow carries a nock 11 which is slotted as at 12 for engagement with the bow string 9.

40 The present invention is concerned with a mechanically operated arrow releasing device, indicated generally by the numeral 13 and shaped generally like a pistol grip having a solid handle or grip portion 14 shouldered on its inner surface as at 15 to receive the forefinger of the archer's hand which, during the operation of the device, is clasped about the grip portion 14. The forward end portion of the arrow releasing device 13 extends horizontally and terminates in a downward extension 16. The front face of the latter 45 portion is formed with a vertically extending string receiving groove 17 which is intersected by a nock receiving socket 18 of a suitable size. Adjacent one side margin of the nock socket 18 is a forwardly projecting grooved guide block 19. 50 A curved band spring 20 (see Figs. 2 and 3) has

its inner end portion anchored to the stock of the portion 16 of the releasing device within the socket and on the side thereof opposite the guide block 19. Said band spring 20 projects forwardly and its tension or arrow nock engaging influence may be regulated by a screw 21 whose inner end is adapted to bear against the spring and which is threaded through a curved locking plate 22 hingedly mounted on a pindle 23 carried by a hinge plate 24 secured to one side face of the downturned extension 16 of the releasing device 13. The locking plate 22 also has associated therewith, at a substantial angle to the plane of the plate 22, a pair of spaced latching fingers 25 which, when the device is in its "set" condition, straddle the band spring 20 and extend transversely across the front edge of the portion 16, above and below the socket 18, in the manner best shown in Fig. 3, being releasably retained in this position by shouldered latch dogs 26. In the latter operative, secured position of the fingers 25, the curved locking plate 22 assumes the position of Figs. 2, 3 and 5, with the screw 21 impinging against the free end of the band spring 20, placing the same under tension to cause it to frictionally bear against the adjacent side of the arrow nock 11, which is seated within the socket 18, as in Figs. 3 and 5.

One side face of the forward end of the grip shaped member 13 is recessed to movably house the trigger and latch mechanism, as shown in Fig. 2, wherein the plate 27, which closes the recesses and confines the mechanism, is shown as being removed. As will appear from Fig. 2 the forwardly projecting latch dogs 26 are in fact integral with the body portion of a vertically reciprocating plate 28 having enlarged slots 29 therein to receive fixed guide pins 30. The dog plate 28 is adapted to be reciprocated upwardly against the tension of a confined coiled spring 31 bearing against a flanged upper end portion of the plate 28. Pivotaly mounted within an enlarged elongated recess therefor in the upper portion of the member 13 is a trigger lever 32 having its rear end projecting out of the handle extension above the grip portion 14 and provided with a thumb plate 33. The inner end portion of the trigger lever 32 is angled and extends under a shoulder 34 at the upper end of the dog plate 28. Hence, when the thumb plate 33 of the trigger lever 32 is pressed downwardly, the inner end portion of the trigger lever 32 will kick or reciprocate the dog plate 28 upwardly, against the tension of the spring 31, raising the shouldered outer ends of the dogs 26 from their engaging relation with the "cocked" latch fingers 25, whereby said released latch fingers, under the influence of the band spring 20 bearing against the curved plate 22, will hingedly move said plate and fingers from the position shown in the drawing to a position at right angles thereto. When thumb pressure is removed from the thumb plate 33 of the trigger lever 32, the spring 31 will lower the dog plate 28 to its normal position.

The operation and utility of the improved arrow releasing device should be apparent from the preceding descriptive matter. However, to summarize, the nock 11 of the arrow 10 has its slot engaged with the bow string 9 in the usual manner. The nock is, however, mechanically releasably secured to the bow string by means of the device 13 which, prior to being engaged and "set," has the latching fingers 25 released so as not to obstruct the string recess 17 and the nock socket

18. The arrow nock is thereupon inserted into the socket 18 of the device with the adjacent portion of the engaged bow string 9 being accommodated by the groove or recess 17. The curved locking plate 22 is next pressed so as to carry the 5 latching fingers 25 transversely across the front of the device 13 and the same snap under the shoulders of the latching dogs 26, whereby the device 13 becomes attached to the arrow nock and bow string and is in its set condition. One 10 side of the arrow nock will seat within the recess of the guide block 19, which because of its length provides ample bearing surface. The other side of the arrow nock is firmly engaged by the band spring 20 which is then under tension. Through 15 the means described, the frictional restraint on the engaged portion of the arrow nock is always uniform and there is a consequent uniform release of the arrow when the trigger lever is operated for arrow releasing purposes.

Although a plurality of arrows 10 are intended to have nocks of uniform diameter, in practice there may be slight deviations ranging from $\frac{1}{4}$ " to $\frac{1}{2}$ of an inch. The socket 18 is sufficiently large to receive arrow nocks within these size 20 ranges and the band spring 20, engaging one side of the arrow nock, insures a frictional engagement with an arrow nock regardless of possible size deviation. Furthermore, as previously stated, the adjusting screw 21 may be utilized for varying the tension of the band spring 20.

With the device engaged with the arrow nock 11 and bow string 9, as previously mentioned, the archer then grasps with one hand the grip portion 14 of the device 13 and pulls the bow string 35 9 and engaged arrow 10 rearwardly until the string is sufficiently taut or retracted for shooting purposes. Then, after taking aim, the archer at the desired moment presses downwardly on the thumb plate 33 with his thumb, thereby raising the dog plate 28 and disengaging the latching fingers 25 which, under the influence of the spring 20, then snap forwardly to a position at right angles to that of Fig. 3.

The engaged bow string is released and the 45 frictional restraint on the arrow nock is overcome with the result that the arrow is shot from the released bow string in a smooth accurate manner.

From the foregoing description it will be evident that the improved arrow releasing device is 50 of very simple construction, is easy, accurate and smooth in its operation, and is well adapted for the purposes described.

What is claimed as the invention is:

55 1. A device for securing an arrow to a bow string and releasing the arrow for shooting purposes, comprising a grip member formed at its forward end with a nock socket adapted to be entered by an arrow nock and engaging bow string, a locking plate pivotally carried by the grip member laterally of said nock socket and including bow string engaging fingers, a spring having an end portion carried by said grip member and extending between said locking plate and an arrow nock within said socket and exerting pressure against the plate and nock, and a trigger operated mechanism associated with the grip member and releasably engageable with said fingers to hold the same in bow string confining position, manual release of the trigger operated mechanism reducing the spring tension on the arrow nock and permitting said spring to urge the locking plate and fingers to an inoperative position.

70 2. A device for securing an arrow to a bow

string and releasing the arrow for shooting purposes, comprising a grip member formed at its forward end with a nock socket adapted to be entered by an arrow nock and engaging bow string, a locking plate pivotally carried by the grip member laterally of said nock socket and including bow string engaging fingers, a band spring secured at an end portion to said grip member and having reversely curved portions extending between and exerting reverse pressures against the plate and the nock of an arrow within the socket, and a trigger operated mechanism operatively carried by the grip member and releasably engageable with said fingers to hold the same in bow string confining position, operation of the trigger mechanism being effective to release said fingers with the plate being swung to inoperative position by said spring and the spring tension against the arrow nock also being reduced.

3. A device for securing an arrow to a bow string and releasing the arrow for shooting purposes, comprising a grip member formed at its forward end with a nock socket adapted to be entered by an arrow nock and engaging bow string, 25 a locking plate pivotally carried by the grip

member laterally of said nock socket and including bow string overlying fingers, a spring carried by the grip member between said locking plate and a side of said socket to form a yieldable side wall for the latter and reacting against said plate for urging the latter to an inoperative position, a spring urged latching dog plate reciprocatably mounted on the grip member and releasably engageable with said overlying fingers to hold the same in operative position, the locking plate when in operative position holding said spring in the nock socket in frictional engagement with the side of an arrow nock within said socket, and a trigger for manually operating the latch dog plate.
